CAR WASH STRUCTURE

James W. Baker, Santa Monica, Calif., assignor to Hunter
Structures, Inc., Los Angeles, Calif.

Filed July 20, 1970, Ser. No. 24,026

Term of patent 14 years

Int. Cl. D25—04

U.S. Cl. D13—1

FIG. 1.

FIG. 1 is a front elevational view of a car wash structure showing my new design;

FIG. 2 is a rear elevational view;

FIG. 3 is an end or side elevational view.

I claim:

The ornamental design for a car wash structure, as shown.
